The ornamental design for an organizer with vertical storage sections and end storage compartments, as shown and described.

DESCRIPTION

FIG. 1 is a front, top and right side perspective view of an organizer with vertical storage sections and end storage compartments, showing my new design;

FIG. 2 is a top plan view thereof;

FIG. 3 is a front elevational view thereof, the rear elevational view being identical;

FIG. 4 is a left side view thereof, the right side view being identical; and,

FIG. 5 is a bottom plan view thereof.
